WALL CLOCK

Karl W. Effers, Sr., 9599 Sunset Blvd.,
Beverly Hills, Calif. 90210

Filed June 28, 1967, Ser. No. 7,624

Term of patent 14 years

(Cl. D42—7)

FIG. 1 is a front elevational view of a wall clock showing my new design;

FIG. 2 is a top plan view; and

FIG. 3 is a left side elevational view.

I claim:

The ornamental design for a wall clock, substantially as shown.
